CONTROL FOR PUNCH PRESS

Waldemar C. Ewaldson, Millington, and Alfred A. Williams, Plainfield, N. J., assignors to Western Electric Company, Incorporated, New York, N. Y., a corporation of New York

Application September 4, 1953, Serial No. 378,478

5 Claims. (Cl. 164—111)

This invention relates to controls for presses and particularly to controls for turret type punch presses.

The commercially known turret type punch presses, having turrets mounted on aligned axes for supporting spaced sets of punch and die units adapted to be moved singly into operating position in alignment with the ram of the press, are provided with locking mechanisms including tapered pins receivable in tapered recesses in the turrets to lock the turrets with the selected set of punch and die in the operating position.

If the tapered pins are driven all the way home in their recesses, the turrets will be locked not only against rotation but in positions whereby the chosen set of punch and die will be positioned accurately in the operating position. It has been found that defective punching operations are the result of the operator failing to move the locking pins far enough into their recesses to accomplish accurate positioning of the turrets particularly the chosen punch and die set with respect to the ram of the press.

The object of the invention is a control for a press of this type to maintain the press against operation until the latching or locking means has been operated to assure accurate locking of the turrets.

With this and other objects in view, the invention comprises a control for a press having punch and die turrets movable in selective sets into their operating position where the selected punch is positioned for actuation by a ram under the control of a clutch releasing rod, and tapered latch pins receivable in similarly tapered recesses of the turrets and moved into and out of latching position by a manually actuatable mechanism. The control is connected directly to the pin moving mechanism to apply added force to the pins to assure setting thereof prior to the actuation of the clutch release rod.

Other objects and advantages will be apparent from the following detailed description when considered in conjunction with the accompanying drawing, wherein:

Fig. 1 is a fragmentary side elevational view of a turret type press embodying the invention,

Fig. 2 is a front elevational view of the conventional clutch and the trip-rod therefore for the press, and

Fig. 3 is a fragmentary sectional view of the reciprocable ram and driving means therefor.

A press 10 is of the commercially known type having a reciprocable ram 11 moved through single cycles under the control of a clutch 12 actuatable into operative engagement with the shaft 14 through movement of a pull rod 15. In the press selected to illustrate the invention a flywheel 3, which is a part of the driving means, is mounted for free rotation on the crank shaft and is driven by a belt 4 connected to a power means (not shown). The conventional clutch 12 includes members (not shown) connected respectively to the flywheel 3 and the crank shaft 14 and normally held disconnected by an arm 5 until the arm is actuated by the pull rod 15. Fig. 3 illustrates the crank shaft connected to the ram 11 through a crank arm 6.

The press is provided with the conventional turrets

2

16 and 17 supporting punch holders 18 and die holders 19 respectively. The turrets are supported at 20 and 21 on aligned axes for movement of their sets of punch and die holders into the operating position in alignment with the ram 11. Tapered latch pins 22 and 23, receivable in similarly tapered recesses 24 and 25, are supported in apertures of the main body of the press and have their innermost ends pivotally connected to a yoke 26. Although the tapered pins are provided with springs 25 normally urging them into locking engagement with the turrets, it has been found that if the turrets are not moved to accurately align the sets of recesses 24 and 25 with the pins, there is not sufficient force in the springs 27 to rock the turrets to bring the selected recesses into accurate alignment therewith to permit the pins to fully seat themselves.

The pins 22 and 23, together with the yoke 26, are operatively connected to a manually actuatable mechanism including a lever 30 mounted fixedly on a shaft 31 which is supported in suitable bearings not shown. The lower end of the lever 30 is connected directly or through the aid of a link 32 to the yoke 26. Another lever 33, fixedly mounted on the shaft 31, is connected by the aid of a rod 34 to a member 35 which is rotatably mounted on a shaft 36. It will be noted that the connection 37 between the rod 34 and the member 35 is eccentric with respect to the axis of the shaft 36 so that rocking movement of the member 35 through the aid of a handle 38 between the dotted line position and the solid line position 30 will cause actuation of the rod 34, to move the lever 33 and to rock the shaft 31, to actuate the remaining portion of the mechanism, to move the pins toward the recesses of the turrets.

The control for the press includes an arm 40 fixed to the shaft 31 and having its outer end disposed with respect to a microswitch 41 while a yoke 42 of a piston rod 43 of an air cylinder 44 is connected to the element intermediate its ends. The air cylinder 44 is supported at 45 and has a fluid or air line 46 extending from a main supply line 47 through a normally closed electromagnetic valve 48 to the top of the cylinder.

Returning to the member 35, it will be noted that this member is somewhat in the form of a circular cam having a high portion 50 and a low portion 51, the low portion 45 being in registration with a microswitch 52 when the arm 38 is in the dotted line, normal or idle position. The switches 52 and 41 and the electromagnetic valve 48 are in a circuit including lead lines 55 and 56. This circuit is so arranged that when the member 35 is actuated to 50 operate the mechanism to start the pins 22 and 23 into a selected set of apertures 24 and 25, the arm or element 40 will move sufficiently about the axis of the shaft 31 to operate the switch 41. The switch 41 having been closed and the high portion 50 of the element 35 55 having closed the microswitch 52, the valve 48 is energized into open position, opening the air line to the top of the air cylinder 44, thereby adding greater force through the arm or element 40 to the latch operating mechanism to cause the tapered pins, if necessary, to bring about final rocking movements of the turrets to accurately align the chosen set of punch and dies with the ram and to drive the latch pins home to assure against possible rocking movement of the turrets prior to or during the operating cycle of the press.

65 The operating means for the clutch 12 depends for its function on the completion of the latching means for the turrets. The pull rod 15 for the clutch 12 is connected to a yoke 60 of a piston rod 61 of an air cylinder 62, which is mounted at 63 on the press. An air line 64 70 extends from the air line 46 at the left of the valve 48 and extends through a solenoid operable valve 65 to the top of the air cylinder 62. Although suitable exhausting

means for the air cylinders 44 and 62 have not been described, it should be understood that the conventional exhausting means or valves have been provided therefor.

The solenoid valve 65 is disposed in a circuit with a switch 66 which, in the present instance, is of the foot type switch and a timing unit 67, which may be of any desired type such as a time delay relay or any of the commercially known units. Furthermore, it will be noted that this circuit depends on the closing of the switches 41 and 52 and cannot be completed until these switches have been closed. This circuit may be traced from line 55 through switch 52 when closed, switch 41 when closed, switch 66 when closed, through the timing unit 67, the winding of the electromagnetic valve 65, through connection 68 to line 56.

Considering now the function of the control for the press, let it be assumed that the arm 38 for the element 35 is in the dotted line position with the mechanism for the latch pins in a position to hold the pins free of the turrets 16 and 17. At this time, the element 40 has been raised, or moved counterclockwise, free of the switch 41 and it is possible for the operator to move the turrets 16 and 17 to position any desired set of punch and die as accurately as he possibly can, visually in the operating position. The operator then moves the arm 38 from the dotted line position to the solid line position, moving the mechanism connecting the member 35 to the pins 22 and 23, to move the pins toward their turrets. If the recesses are not in general alignment with the pins, the pins will be caused to strike the outer peripheries of their respective turrets, preventing movement of the member 35 sufficiently to complete closing of either switch 52 or 41. However, if the recesses are disposed in general but not perfect alignment with the pins, it is possible for the operator to move the member 35 sufficiently to close the switch 52, moving, at the same time, the element 40 to close the switch 41. When this has been accomplished, the closed switches 52 and 41 will complete a circuit through the electromagnetic valve 48 operating into open position to admit air under pressure to the top of the air cylinder 44 which will supply an added force to the element 40 rocking the shaft 31 to move the lever 30 to force the yoke 26 with the pins 22 and 23 until the pins have been seated in their respective recesses.

If, by chance, the operator should close the switch 66 prior to the completion of the latching means, the unit 67 will provide a sufficient delay in the energization of the valve 65 to allow complete setting of the pins prior to the admission of air under pressure into the air cylinder 62 to actuate the pull rod 15 to release the clutch 12.

With this control, defective parts resulting from inaccurate positioning of the punch and die units in the operating position of the press will be eliminated because accurate alignment and positive holding of the turrets against movement during each operating cycle of the press will be assured.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. A control for a press having a crank shaft adapted for connection to a driving means through a normally disengaged one revolution clutch when a rod is actuated to engage the clutch, turrets for sets of punches and dies movable relative to an operating position to selectively locate sets of the punches and dies singly therein where a ram reciprocated by the crank shaft will move the selected punch through an operating cycle, and tapered latch pins receivable in similarly tapered recesses of the turrets and movable into and out of latching positions

5 by an actuatable mechanism, the control comprising a unit operable to actuate the clutch rod, auxiliary means operable to cause the mechanism to force the pins into the recesses, means actuatable by the mechanism to cause operation of the auxiliary means after said mechanism causes the pins to enter the recesses and actuatable means rendered effective after the auxiliary means has been operated to operate the unit.

2. A control for a press having a crank shaft adapted 10 for connection to a driving means through a normally disengaged one revolution clutch when a rod is actuated to engage the clutch, turrets for sets of punches and dies movable relative to an operating position to selectively locate sets of the punches and dies singly therein where a ram reciprocated by the crank shaft will move the selected punch through an operating cycle, and tapered latch pins receivable in similarly tapered recesses of the turrets and movable into and out of latching positions by an actuatable mechanism, the control comprising a unit 15 operable to actuate the clutch rod, an element operatively connected to the mechanism and movable thereby during movement of the pins, auxiliary means operatively connected to the element and operable to cause the mechanism to force the pins into the recesses, means actuatable by the mechanism to cause operation of the auxiliary means after said mechanism causes the pins to enter the recesses, and actuatable means rendered effective after the auxiliary means has been operated to operate the unit.

3. A control for a press having a crank shaft adapted 20 for connection to a driving means through a normally disengaged one revolution clutch when a rod is actuated to engage the clutch, turrets for sets of punches and dies movable relative to an operating position to selectively locate sets of the punches and dies singly therein where a ram reciprocated by the crank shaft will move the selected punch through an operating cycle, and tapered latch pins receivable in similarly tapered recesses of the turrets and movable into and out of latching positions by an actuatable mechanism, the control comprising a unit 25 operable to actuate the clutch rod, an element operatively connected to the mechanism and movable thereby during movement of the pins, auxiliary means operatively connected to the element and operable to cause the mechanism to force the pins into the recesses, means actuatable by the mechanism to cause operation of the auxiliary means after said mechanism causes the pins to enter the recesses, and actuatable means rendered effective after the auxiliary means has been operated to operate the unit.

4. A control for a press having a crank shaft adapted 30 for connection to a driving means through a normally disengaged one revolution clutch when a rod is actuated to engage the clutch, turrets for sets of punches and dies movable relative to an operating position to selectively locate sets of the punches and dies singly therein where a ram reciprocated by the crank shaft will move the selected punch through an operating cycle, and tapered latch pins receivable in similarly tapered recesses of the turrets and movable into and out of latching positions by an actuatable mechanism, the control comprising a unit 35 operable to actuate the clutch rod, an element operatively connected to the mechanism and movable thereby during movement of the pins, auxiliary means operatively connected to the element and operable to cause the mechanism to force the pins into the recesses, means energizable to cause operation of the auxiliary means, a first switch actuatable into closed position by the element after the pins enter the recesses and included in a circuit with the energizable means, and a second switch in the circuit including the first switch and the energizable means to cause operation of the unit.

5. A control for a press having a crank shaft adapted

for connection to a driving means through a normally disengaged one revolution clutch when a rod is actuated to engage the clutch, turrets for sets of punches and dies movable relative to an operating position to selectively locate sets of the punches and dies singly therein where a ram reciprocated by the crank shaft will move the selected punch through an operating cycle, and tapered latch pins receivable in similarly tapered recesses of the turrets and movable into and out of latching positions by an actuatable mechanism, the control comprising a unit operable to actuate the clutch rod, an element operatively connected to the mechanism and movable thereby during movement of the pins, a first fluid operable unit connected to the element and adapted to force the pins into the recesses, a line for fluid under pressure to the first unit, means normally closing the fluid line energizable to open

10
15

the line to the first unit, a first switch actuatable by the element to close a circuit including the energizable means, a second fluid operable unit adapted to actuate the clutch rod, a fluid line to the second unit normally closed by an auxiliary means energizable into open position, and a second switch included in a circuit with the first switch and the auxiliary means to cause operation of the second unit after the first unit has been operated to seat the pins in the recesses.
